Primary Examiner — Marianne Pandozzi(74) *Attorney, Agent, or Firm* — Nath, Goldberg & Meyer; Jerald L. Meyer**CLAIM**

The ornamental design for a liquid dispenser and filter, as shown and described.

DESCRIPTION

FIG. 1 is a perspective view of a design for a liquid dispenser with the tray in an extended position;

FIG. 2 is a left side elevational view of the design for a liquid dispenser at an extended position as seen in FIG. 1; right side being a mirror image;

FIG. 3 is a front elevational view of the design for a liquid dispenser at an extended position as seen in FIG. 1;

FIG. 4 is a top planar view of the design for a liquid dispenser with the tray in an extended position;

FIG. 5 is a perspective view of the design for a liquid dispenser with the tray in a folded position;

FIG. 6 is a left side elevational view of the design for a liquid dispenser with the tray in a folded position as seen in FIG. 5; left side being a mirror image;

FIG. 7 is a front elevational view of the design for a liquid dispenser with the tray in a folded position as seen in FIG. 5; and,

FIG. 8 is a top planar view of the design for a liquid dispenser with the tray in a closed position as seen in FIG. 5.
